UNITED STATES PATENT OFFICE.

FRED J. KLINE, OF BAYVILLE, NEW YORK.

FASTENER.

Application filed February 18, 1927. Serial No. 168,510.

This invention relates to fasteners which are used to secure letters, documents and the like for filing, and particularly to fasteners having two spaced tongues which pass through the papers to be secured and through similarly spaced perforations in a retainer or keeper over which the tongues are bent.

It is the object of the present invention to avoid certain defects of such fasteners as heretofore known and to provide a fastener which will hold the assembled papers securely, can be manipulated easily, is light and, nevertheless, sufficiently stiff and has no flanges or lips projecting substantially above the plane of the uppermost sheet of the file.

Other objects and advantages of the invention will be indicated as it is described in the following specification with reference to the accompanying drawing, in which

Fig. 1 is a sectional view of a file illustrating the application of the improved fastener thereto;

Fig. 2 is a perspective view of the fastener;

Fig. 3 is a plan view of the keeper;

Fig. 4 is an enlarged transverse section on the line 4—4 of Fig. 3;

Fig. 5 is another transverse section similar to Fig. 4 and showing modified locks; and

Fig. 6 is a transverse section through the device showing another modification.

Referring to the drawing, 5 indicates the base of the fastener, having spaced tongues 6 formed integrally therewith and adapted to be bent as indicated and to pass through the file of papers 7. The ends of the tongues 6 project through perforations 8 near the ends of a keeper 9 which rests upon the uppermost paper of the file.

The keeper 9 consists of a strip of metal having two longitudinal ribs 10 on the face or upper surface thereof, the ribs being formed by pressing or otherwise forcing up the body of strip. Two sliding locks 11 are mounted on the keeper 9. These locks are metal strips slightly depressed between the ribs and having their ends 12 bent over the flanges 13 at the sides of the keeper. The locks are preferably cut away at 14, so that when they are disposed contiguously the thumb or finger-nail may be inserted to separate them and permit movement thereof toward the ends of the keeper. The purpose of the locks is to securely hold the ends

of the tongues 6 which, after passing through the perforations 8 in the keeper, are bent inwardly and downwardly into the depression or groove 9' between the ribs 10. The locks, which may be moved to either end of the keeper, can be slipped over the ends of the tongues, and will be held frictionally in adjusted position because of resilience of the tongue. If the file is relatively thin the ends of the tongues will be long and the locks may be disposed near the center of the keeper. When the projecting ends of the tongues are shorter, because of increased thickness of the file, the locks will be spaced apart, each covering the end of one of the tongues. Although two locks are desirable, one may be used especially when the files are relatively thin or the tongues are long.

The ribs 10 serve several purposes. As already noted, they provide a depression or groove to receive the ends of the tongues 6 so that the latter can be held by the locks 11 below the plane of the upper surface of the ribs. The tongues are thus prevented from projecting in such a way as to catch and tear papers which may be inserted in the file above the keeper. The ribs stiffen the keeper so that relatively light metal can be used for the body thereof and they permit the edges or flanges 13 to be close to the plane of the uppermost paper of the file so that the danger of catching papers on the flanges is minimized.

Another and important function of the ribs 10 is to prevent escape of the locks from the keeper. In pressing the ribs from the strip of metal the edges of the flanges 13 are drawn in slightly but as the ribs do not extend to the ends 15 of the keeper these ends are somewhat flared as indicated in an exaggerated manner in Figs. 2 and 3 of the drawing. The locks 11 are applied to the keeper after the latter has been formed and slide freely on the keeper between the ends 15. They cannot, however, pass over the flared ends. The ends 15 are, preferably, slightly depressed from the plane of the body of the keeper to rest upon the uppermost paper of the file and to facilitate movement of the locks.

In Fig. 5 of the drawing the ends 16 of the locks 17 are turned upwardly into the grooves 18 formed in the lower face of the keeper 19 by striking up the ribs 20 thereon. As in the preceding embodiment

of the invention, the ribs 20 terminate short of the ends of the keeper and consequently the ends 16 of the locks cannot escape from the grooves. Removal of the locks is thus prevented.

In Fig. 6 the flanges 13 are omitted and ribs 21 are formed at the edges of the keeper. The ends 22 of the locks 11 are turned upwardly into the grooves 23 in the lower face 10 of the keeper. The ribs 21 may terminate short of the ends of the keeper as in the preceding embodiments of the invention.

The keeper as described affords a secure fastening for the ends of the tongues 6 and 15 firmly binds the papers in the file. The keeper can, however, be removed easily by sliding the locks to release the tongues. The locks can be moved in the desired direction for that purpose by slight pressure of the 20 thumb or finger.

Various changes can be made within the scope of the accompanying claims without departing from the invention or sacrificing any of the advantages thereof.

25 I claim:

1. A fastener comprising a base having spaced tongues and a keeper with similarly spaced perforations to receive the tongues, longitudinal ribs on the upper face of the 30 keeper extending continuously between the ends thereof but terminating short of the ends, a plurality of locks adapted to overlie the ends of the tongues when the latter are threaded through the perforations and bent 35 into the groove between the ribs, and stops for the locks formed at the ends of the keeper.

2. A fastener comprising a base having spaced tongues and a keeper with similarly 40 spaced perforations to receive the tongues, longitudinal ribs on the upper face of the keeper extending continuously between the ends thereof but terminating short of the ends and a plurality of locks adapted to overlie the ends of the tongues when the latter are threaded through the perforations and bent 45 into the groove between the ribs, the ends of the locks being bent over the lateral edges of the keeper and projecting into grooves formed on the underside of the keeper.

3. A fastener comprising a base having spaced tongues and a keeper with similarly 50 spaced perforations to receive the tongues, longitudinal ribs on the upper face of the keeper extending continuously between the ends thereof but terminating short of the

ends and a plurality of locks adapted to overlie the ends of the tongues when the latter are threaded through the perforations 60 and bent into the groove between the ribs, the ends of the locks being bent over the lateral edges of the keeper and the ends of the keeper being flared to retain the locks 65 thereon.

4. A fastener comprising a base having spaced tongues and a keeper with similarly spaced perforations to receive the tongues, longitudinal ribs on the upper face of the keeper extending continuously between the ends thereof but terminating short of the ends and a plurality of locks adapted to overlie the ends of the tongues when the latter are threaded through the perforations 70 and bent into the groove between the ribs, 75 the locks being depressed between the ribs.

5. A fastener comprising a base having spaced tongues and a keeper with similarly spaced perforations to receive the tongues, longitudinal ribs on the upper face of the 80 keeper extending continuously between the ends thereof but terminating short of the ends and a plurality of locks adapted to overlie the ends of the tongues when the latter are threaded through the perforations 85 and bent into the groove between the ribs, the locks being cut away slightly at their lateral edges.

6. A keeper for fasteners having perforations adjacent its ends, longitudinal ribs extending continuously between the ends but terminating short of the ends and a plurality of locks slidably mounted on the keeper, the ends of the locks being bent over the lateral edges of the keeper and the 90 ends of the keeper being flared to retain the locks thereon.

7. A keeper for fasteners having perforations adjacent its ends, longitudinal ribs extending continuously between the ends but terminating short of the ends and a plurality of locks slidably mounted on the keeper, the locks consisting of metal strips 100 depressed between the ribs.

8. A keeper for fasteners having perforations adjacent its ends, longitudinal ribs extending continuously between the ends but terminating short of the ends and a plurality of locks slidably mounted on the keeper, the locks consisting of metal strips 105 cut away slightly at their lateral edges.

In testimony whereof I affix my signature.

FRED J. KLINE.

of the invention, the ribs 20 terminate short of the ends of the keeper and consequently the ends 16 of the locks cannot escape from the grooves. Removal of the locks is thus prevented.

In Fig. 6 the flanges 13 are omitted and ribs 21 are formed at the edges of the keeper. The ends 22 of the locks 11 are turned upwardly into the grooves 23 in the lower face 10 of the keeper. The ribs 21 may terminate short of the ends of the keeper as in the preceding embodiments of the invention.

The keeper as described affords a secure fastening for the ends of the tongues 6 and firmly binds the papers in the file. The keeper can, however, be removed easily by sliding the locks to release the tongues. The locks can be moved in the desired direction for that purpose by slight pressure of the 20 thumb or finger.

Various changes can be made within the scope of the accompanying claims without departing from the invention or sacrificing any of the advantages thereof.

25 I claim:—

1. A fastener comprising a base having spaced tongues and a keeper with similarly spaced perforations to receive the tongues, longitudinal ribs on the upper face of the 30 keeper extending continuously between the ends thereof but terminating short of the ends, a plurality of locks adapted to overlie the ends of the tongues when the latter are threaded through the perforations and bent into the groove between the ribs, and stops 35 for the locks formed at the ends of the keeper.

2. A fastener comprising a base having spaced tongues and a keeper with similarly 40 spaced perforations to receive the tongues, longitudinal ribs on the upper face of the keeper extending continuously between the ends thereof but terminating short of the ends and a plurality of locks adapted to overlie the ends of the tongues when the latter are threaded through the perforations 45 and bent into the groove between the ribs, the ends of the locks being bent over the lateral edges of the keeper and projecting 50 into grooves formed on the underside of the keeper.

3. A fastener comprising a base having spaced tongues and a keeper with similarly 55 spaced perforations to receive the tongues, longitudinal ribs on the upper face of the keeper extending continuously between the ends thereof but terminating short of the

ends and a plurality of locks adapted to overlie the ends of the tongues when the latter are threaded through the perforations 60 and bent into the groove between the ribs, the ends of the locks being bent over the lateral edges of the keeper and the ends of the keeper being flared to retain the locks 65 thereon.

4. A fastener comprising a base having spaced tongues and a keeper with similarly spaced perforations to receive the tongues, longitudinal ribs on the upper face of the keeper extending continuously between the 70 ends thereof but terminating short of the ends and a plurality of locks adapted to overlie the ends of the tongues when the latter are threaded through the perforations and bent into the groove between the ribs, 75 the locks being depressed between the ribs.

5. A fastener comprising a base having spaced tongues and a keeper with similarly spaced perforations to receive the tongues, longitudinal ribs on the upper face of the 80 keeper extending continuously between the ends thereof but terminating short of the ends and a plurality of locks adapted to overlie the ends of the tongues when the latter are threaded through the perforations 85 and bent into the groove between the ribs, the locks being cut away slightly at their lateral edges.

6. A keeper for fasteners having perforations adjacent its ends, longitudinal ribs extending continuously between the ends but terminating short of the ends and a plurality of locks slidably mounted on the keeper, the ends of the locks being bent over the lateral edges of the keeper and the 95 ends of the keeper being flared to retain the locks thereon.

7. A keeper for fasteners having perforations adjacent its ends, longitudinal ribs extending continuously between the ends but terminating short of the ends and a plurality of locks slidably mounted on the keeper, the locks consisting of metal strips 100 depressed between the ribs.

8. A keeper for fasteners having perforations adjacent its ends, longitudinal ribs extending continuously between the ends but terminating short of the ends and a plurality of locks slidably mounted on the keeper, the locks consisting of metal strips 105 cut away slightly at their lateral edges.

In testimony whereof I affix my signature.
